UNITED STATES PATENT OFFICE.

JOHN CARLYLE BLANTON AND DOUGLAS JOHNSON SEXTON, OF FREEMAN, WEST VIRGINIA.

MAIL-BAG-DELIVERING APPARATUS.

1,216,056.

Specification of Letters Patent. Patented Feb. 13, 1917.

Application filed June 3, 1916. Serial No. 101,623.

To all whom it may concern:

Be it known that we, JOHN C. BLANTON and DOUGLAS J. SEXTON, both citizens of the United States, and residents of Free-
5 man, in the county of Mercer and State of West Virginia, have invented a new and Improved Mail-Bag-Delivering Apparatus, of which the following is a full, clear, and exact description.

10 General objects of our invention are to provide improved means for transferring mail from a car to a stationary stand at a station or the like, or from such a stand to the car without mutilating the mail or the
15 bag; to provide an apparatus of the indicated character involving the minimum expense for its construction and operation, and to provide an apparatus that will deliver a full bag with equal facility and precision
20 as with a bag partly full, and which will deliver two or more bags at one time.

More particular objects of the invention are to provide bag-holding and releasing means on the car and stand so constructed
25 as to hold the bag steadied on the delivering arm and which will readily respond to the bag detaching means on the car or stand; to provide a mail bag-supporting arm so mounted on the car as to be conveniently
30 adjusted in a projected position for receiving or delivering a mail bag and securely sustained in such position; and to provide for readily and conveniently withdrawing the said arm to a position adjacent to the
35 interior of the car for the manual placing and removal of the mail bag.

Other objects as well as the advantages of our improved construction will appear as the description proceeds.

40 Reference is to be had to the accompanying drawings forming a part of this specification in which similar reference characters indicate corresponding parts in all the views.
Figure 1 is a sectional plan view on the
45 line 1—1, Fig. 2;

Fig. 2 is a front view of a mail bag-delivering apparatus embodying our invention;

50 Fig. 2^a is a fragmentary perspective view of means to hold the mail bag-supporting arm in projected position for receiving and delivering mail;

Fig. 3 is a transverse vertical section of the devices carried by the car;

55 Fig. 4 is a fragmentary perspective view

showing the means for retaining the mail bag on the car or stand for detachment by the receiving means;

Fig. 5 is a fragmentary perspective view showing the means for retaining a received 60 mail bag;

Fig. 6 is a detail in sectional plan view showing a modification of the means on the car for holding the mail bag-supporting arm in a projected position for delivering 65 or receiving a bag;

Fig. 7 is a transverse vertical section on the line 7—7, Fig. 6.

In carrying out our invention in practice in accordance with the illustrated example, the car 10, it will be understood, may be of any approved construction, having a door 11, here conventionally indicated.

A horizontal shaft 12 is rockably supported on the car across the doorway at 75 the front by any suitable means such as brackets 13. The shaft, at the center, is broadened and formed with a transverse hole 14 in which the mail bag-supporting arm 15 is slidable. Preferably, on the shaft 80 12, friction rollers, 16, are provided at the back above and below the arm 15. The arm 15 has a suitable handle 17 at the inner end for manually sliding the same in the opening 14 of the shaft 12, and on said arm 85 are an inner stop collar, or equivalent formation 18, and an outer stop collar 19, or the like, whereby to limit the sliding movement of the said arm in either direction.

At the outer end of the arm 15 is a cross 90 arm 20 having at one end a retaining hook 21. The opposite end of said cross arm is formed with a head, designated generally by the numeral 22, adapted to support a mail bag for delivering the same, the head 95 being provided with a retaining device designated generally by the numeral 23, for releasably holding the mail bag-suspending means.

To hang the mail bag on the head 22, a 100 ring 24 is provided having a snap hook 25 adapted to engage a ring 26, which is held by a strap 27 on the mail bag 29, said bag having guide rings 28 for said strap.

The head 22 includes a central forwardly 105 projected member 30 and two diverging side members 31. The side members 31 are formed at the front ends with vertical notches 32 to receive upstanding members 34 on the ring 24, the upper ends of said 110

members 34 being joined by a cross bar 33 on said ring. The arrangement is such that the cross bar 33 rests on the central member 30 of the head 22, thereby sustaining a suspended mail bag, and the engagement of the upstanding members 34 and notches 32 at each side, steady the ring 24 and prevents swinging of the same on a vertical axis.

The retainer 23 is pivoted as at 23^a on any suitable attachment or formation 30^a on the under side of the central member 30 of the head 22 to rock in a vertical plane, said retainer having a forked formation presenting side arms 35 extending upwardly at the sides of the member 30. At the lower end, below the pivot, the retainer 23 has a depending arm 36 connected with which is one end of a retractile spring 37, the opposite end of which is suitably secured to the head 22 at the under side of the arm 30 or other fixed part of the head 22.

To retain the shaft 12 against vertical rocking movement whereby to sustain the mail bag-supporting arm 15 in the projected position at right angles to the side of the car 10, we employ, in the form shown in Figs. 1, 2 and 2^a, a latch 38 pivoted at its outer end, as at 39, on the shaft 12 and adapted to be swung into a lateral notch 40 in a suitable fixture 41 on the door frame of the car 10.

In the form shown in Figs. 6 and 7, a fixed latch arm 38^a projects rearwardly on the shaft 12^a and is receivable in a vertical notch 40^a in a suitable fixture 41^a on the car at the door frame. A horizontal latch bolt 41^b is mounted in the door frame to extend transversely through the fixture 41^a above the latch 38^a, said bolt having an inwardly extending arm 41^c, whereby the bolt may be manually slid from the interior of the car to engage or disengage the latch 38^a. The arm 41^c is adapted to slide in a slot 41^d in the car. A compression spring 41^e is coiled about the bolt 41^b in a pocket 41^f in the door frame, said spring abutting at one end against the end of said pocket and abutting at the opposite end against a collar 41^g on the latch bolt.

By the described construction by grasping the handle 17, the arm 15 may be moved outwardly or inwardly through the shaft 12 from the full line position, Fig. 3, to the retracted position indicated in dotted lines at the left of said figure. Also, while grasping the handle 17 the arm 15 and shaft 12 may be rocked vertically to bring said arm to a position parallel with the side of the car and adjacent thereto as indicated in dotted lines, Fig. 3.

A stand 42 is erected alongside of the track and is provided with a lower arm 43 and an upper arm 44, projecting in reverse directions from opposite sides of said stand. The arm 43 has a retaining hook 45

at the end and a cross arm 46 rearward of said hook, said cross arm being pivoted at the center as at 47 to turn in a horizontal plane. Retractile springs 48 are secured each at one end to the opposite ends of the cross arm 46 and at their opposite ends said springs are secured to a fixed pin 49 or the like on the main arm 43.

On the arm 44 is formed a head 22^a in all respects the same as the head 22, including a retainer 23^a, corresponding with the retainer 23, whereby a mail bag 29^a (Figs. 1 and 2), may be suspended by the described elements 24, 25, 26, from the head 22^a of the stand.

When the arm 15 is projected to receive a mail bag, the hook 21 of the cross arm 20 will readily pass into the suspending ring 24 on the arm 44 of the stand 42, and the engagement of said ring 24 with the arm 15 will release the said ring from the remaining device 23^a. Similarly, if a bag 29 be suspended from the cross arm 20 on the car, the hook 45 of arm 43 on the stand 42, will pass into the suspending ring 24 until said ring strikes the cross arm 46 which will release the retaining device 23 and detach the suspended mail bag. Any unequal contact of the ring 24 with the arm 46 will be taken care of by the springs 48.

The manner of suspending the mail bag and the means for engaging and releasing the same do not depend on whether the mail bag is full or half full, nor on whether there are one or more mail bags held by the suspending means. It will be observed also, that there is a substantial correspondence between the means on the stand 22 and on the car, both as regards the delivering and receiving means.

It is to be understood that the term "ring" as applied to the element 24 is not intended to limit the device to any actually circular form but to include any equivalent open ring-like element affording an opening therethrough for the detaching arm and from the bottom of which the mail bag may be detachably suspended, the said elements having the side and transverse members at the top to engage with the co-engaging side and intermediate members on the head 22.

Having thus described our invention we claim as new and desire to secure by Letters Patent:

1. In a mail bag-delivering apparatus, a mail bag-supporting arm, and a ring adapted to suspend a mail bag, said ring having approximately vertical members at the sides and a transverse bar joining the said members, and the said supporting arm having a cross arm, one end of which presents, at the sides thereof, laterally projecting members adapted to detachably receive the vertical members of the ring, and an intermediate member forming a rest to detachably receive the transverse bar of the ring.

2. In a mail bag-delivering apparatus, a mail bag-supporting arm, a cross arm thereon presenting a centrally disposed terminal constituting a rest and diverging members 5 at the sides of the central members and formed with vertical notches, a ring, means to suspend a mail bag from said ring at the bottom, said ring presenting vertical members at the sides engageable in said notches, 10 and a cross bar connecting said vertical members and adapted to seat on said rest, and means on the said cross arm yieldingly engaging the cross bar of the ring.
3. In a mail bag-delivering apparatus, a 15 mail bag-supporting arm, a cross arm thereon presenting a centrally disposed terminal constituting a rest and diverging members at the sides of the central members and formed with vertical notches, a ring, means 20 to suspend a mail bag from said ring at the bottom, said ring presenting vertical members at the sides engageable in said notches,
- and a cross bar connecting said vertical members and adapted to seat on said rest, a retainer on the said cross arm yieldingly 25 engaging the cross bar of the ring, the said retainer being pivoted on the said central terminal of the cross arm and having a fork formation presenting arms disposed at the sides of said terminal, and a retractile 30 spring connected with the retainer below the pivot and with the said cross arm.
4. A mail bag-delivering apparatus including a mail bag-supporting arm having a central seat for a mail bag-suspending device, and having members at the sides of said seat; together with suspending means adapted to carry a mail bag, the suspending means including an element adapted to rest on said seat, and presenting members at the 35 sides of said element adapted to detachably engage the members at the sides of the seat.

JOHN CARLYLE BLANTON.
DOUGLAS JOHNSON SEXTON.
